UNITED STATES PATENT OFFICE.

HEINRICH A. W. PETERSEN, OF GARY, INDIANA.

FEED-WATER REGULATOR.

Application filed March 12, 1923. Serial No. 624,457.

My invention relates to regulators for boiler feeds and has for its primary object the provision of a regulator which is efficient, economically manufactured, easily installed, 5 and certain in operation.

Another object of the invention is to provide a regulator having pressure equalizing valves controlled by a balanced arm on which is mounted a hollow member in communication with the boiler, whereby the weight of the hollow member may be varied by automatically changing the contents thereof by the height of the water in the boiler.

A further object of the invention is to provide a regulator having a hollow member communicating with the boiler and operative by differences in weight therein for controlling the flow of water to the boiler.

A still further object of the invention is to 20 improve feed water regulators for generally successful commercial use.

The above and other objects of the invention will be apparent from the following specification and drawings and will be particularly pointed out in the appended claims.

In the drawings, Fig. 1 is an enlarged vertical sectional view of the preferred embodiment of the invention, and

Fig. 2 is a fragmentary portion of a boiler 30 showing the header and a glass with which my invention is used.

In Fig. 1 I have shown a chambered casing formed of top and bottom castings 5 and 6, which have flanges 7 and 8, through 35 which are passed bolts 9 and other fastening means for securing these members in operative relation. The lower casting 6 is provided with an inlet 10 and an outlet 11. These have flanges 12, 13 in which are provided bolt holes 14 at suitable intervals, whereby the flanges may be secured to water pipes. It will be noted that the axes of the inlet and outlet openings are in alignment and in the drawings are shown as horizontally disposed.

The casting 6 is provided with a horizontally disposed bridge 15 in which is screw threaded a valve seat 16 with which a valve 17 cooperates for controlling the flow of liquid from the inlet 10 to the outlet 11. When installed for feed water regulation, the inlet 10 is connected by means of suitable pipe fittings to a pump and the outlet 11 to the boiler. I prefer to mount my regulator above the boiler. The top casting 5 has a threaded collar 18 therein, in the bottom of which is threaded a valve seat member 19, and in the top

of which is threaded another valve seat member 20, the valve seats being indicated at 19^a and 20^a, respectively. I provide a cup-like partition member 21, which is interposed between the flanges 7 and 8 when the top and bottom castings 5 and 6 are secured together. For making a water tight connection the lower face of the flange 7 is formed with an annular tongue 22 and the face of the flange 8 with a corresponding recess 23, the member 21 being provided with a recess 24 for receiving the tongue 22 and a tongue 25 for entering the recess 23. The transverse or bottom portion of the member 21 is provided with a centrally disposed circular opening 26 therethrough which is of a relatively greater diameter than the diameter of the spindle 29 hereinafter described. This permits the fluid or water to flow above the bottom portion of the member 21 regardless of the position of the spindle 29.

The valve 17 has a threaded portion 27 which is adapted to enter a correspondingly shaped recess 28 in the lower end of the stem spindle 29. A set screw 30 is provided for engaging end 31 of the portion 27 for removably securing the valve in position in the spindle. When the valve and spindle are in position with the valve 17 at rest against the seat 16^a the upper end of the spindle 29 is arranged to stop short of the bottom 21^a of the partition member. The upper end of the spindle is provided with a central bore 31 for receiving a cylindrical boss 32 attached to the lower surface of the piston, which is operative above the partition member. The piston comprises top and bottom circular plates 33 and 34 separated by a filler 35 and fastened together by screw threaded members 36. If desirable, the lower plate 34 and the filler 35 may be made integral. The diameter of the filler 35 is less than the diameter of the plates 33 and 34. A packing 36' is inserted around the periphery of the member 35 to prevent the passage of liquid by the piston head. The boss 32 has a by-pass formed therein consisting of a vertically extending portion 37 and a horizontal portion 38, whereby liquid may pass from one side to the other of the piston as conditions may require.

The upper part of the casting 5 is provided with an enlarged threaded opening 39 into which is screwed a plug member 40. This member has a portion counter-bored at 41 to receive packing 42, which is held by another plug 43 threaded into the upper por-

tion of the plug 40. The plugs 40 and 43 are provided with centrally disposed openings 44 and 45 whereby a spindle 46 is permitted to pass. The lower end of the spindle 5 carries valve members 47, 48 which seat against seats 19^a and 20^a under certain conditions. Between the members 19 and 20 a passageway 49 is provided having a threaded end 50 with which a pipe, not shown, may be connected and will lead to the boiler for relief purposes. The upper chamber, that is, the one formed between the partition member 21 and the valve seat member 19 has an upwardly directed passageway 51 terminating in a horizontally disposed annular passage 52 between the seat member 20 and the plug 40. This is also for the purpose of relief.

Cast integrally with the top casting 5 is an upright member 53 having a pivot 54 at its upper end on which is pivoted an arm 55. In the arrangement shown the arm 55 is horizontally disposed. A jaw 56 is connected by means of a pin 57 with the arm 55 and by means of a nut 58 is connected to the upper end of the spindle 46 carrying the valves 47 and 48 for movement of the same under certain conditions. The arm 55 is arranged with relation to the pivot 54 so that a shorter end, that is, the end nearer the pivot, is provided with a sliding weight 59 which by means of a set screw 60 may be secured in selected position along this end of the arm for adjustment purposes. The other end of 35 the arm is provided with forked members 61 which are provided with elongated openings 62 in each of which openings is a pivot 63 secured to a band 64 surrounding a hollow member 65. The member 65 may be substantially cylindrical as shown or may be circular in outline. At the lower end of the member 65 is a connecting nipple 66 and at the upper end is a similar connecting nipple 67.

The boiler shown in Fig. 2 has laterally extending leads 68, 69 in communication with the water space of the boiler and which leads enter a header 70. The water glass 71 is in communication with the header 70 by connections 72, 73. The glass 71 and the header 50 70 are so arranged that the height of the water in the glass will be the same as in the header. Leading outwardly from the middle portion of the header 70 is a flexible pipe, preferably of copper, 74 and which is connected to the threaded nipple 67 of the hollow member 65. A bend 75 may be interposed in the pipe for purposes of flexibility. A similar pipe is connected with the lower connecting nipple 66 of the hollow member 60 65 and leads into the boiler at 76.

The operation of the device is as follows:

The arrangement of the valves shown in Fig. 1 is that when the valves are closed and no water is flowing to the boiler. The pipe 65 74 conducts steam to the interior of the mem-

ber 65 through the nipple 67 when the water level in the boiler is below the top of the connection between the pipe 74 in the header 70. This steam condenses slightly and is returned to the boiler through the nipple 66 70

and the pipe 76. The parts are so arranged that when the water level is below the high level the weight 59 will raise the hollow member 65 raising the valves 47 and 48 from their seats 19^a and 20^a. The water or other liquid 75

on the inlet side 10 of the regulator is under pressure. Therefore as the water enters the lower chamber it bears against the undersurface of the lower plate 34 of the piston by reason of the opening 26 through the partition member 21 and some of the water passes through the by-pass 37 and 38 to the upper side of the piston. The pressure against the

lower side of the piston tends to raise the valve 17 from its seat 16^a, whereupon liquid 85 flows from the inlet 10 through the outlet 11 through a feed line (not shown) to the boiler. As the water fills the lower chamber and tends to raise the piston, some of it will pass to the upper side of the 90

piston through the by-pass and fill the space in the upper chamber and will also fill the annular space 52, with some of the water passing to the boiler through the space 49 and its associated connections. By reason 95

of the pressure of the incoming liquid there will be a greater pressure on the underside of the piston than on the top, tending to raise the piston to its maximum limit owing to the fact that the pump pressure is normally 100 greater than the boiler pressure. For limiting the upward movement of the piston a key 77 is provided passing through the spindle 29 and the boss 32 and projecting laterally 105 of the spindle so as to bear against the underside of the portion 21^a of the partition. The key is retained against movement by cotter pins 78 or other suitable fastening means.

As the pressure on the upper and lower sides of the piston tends to become equalized the 110 piston will approach a state of equilibrium and therefore will be subject to any slight variation in pressure on either side. The device is preferably so arranged that the weight 59 balances the member 65 when it is half full 115 of water. As long as the water level in the boiler is below the predetermined high level, which is that indicated at 79, in Fig. 2, steam will pass through the pipe 74 to the hollow member 65, be condensed and returned to the 120 boiler. As soon as the water reaches the line 79 admission of steam to the hollow member 65 will be cut off and water will therefore flow through the pipe 74 into the hollow member 65 by reason of the vacuum created by the 125 condensation of the steam in the member 65 thereby increasing the weight of the hollow member and causing the same to drop. Such action closes the valves 47 and 48 against 130 their seats and closes the compartment above

the piston and equalizes the pressure on both sides of the piston. Hence, as the water from the inlet 10 continues to enter the lower chamber it will pass to the upper side of the piston 5 through the by-passes 37 and 38 until the valve 17 is seated. When equalization of pressure on both sides of the piston has taken place, the kinetic energy of the fluid, assisted by the weight of the valve, valve stem and 10 piston, causes the closing of the valve 17. This condition prevails until the water level falls below the line 79 whereupon the steam is again admitted to the hollow member 65 and the water contained therein will drain 15 back into the boiler through the nipple 66 and connecting pipe 76 by reason of the member 65 being positioned above the water level in the boiler. As soon as the member 65 is free of water it is raised by the action of the 20 weight 59 opening the valves 47 and 48 thereby reducing the pressure in the chamber above the piston to that of the boiler pressure, permitting the piston to be raised again by the pressure of the water coming in from 25 the inlet 10 which of course is greater than the boiler pressure. It will of course be noted that when the valves 47 and 48 are seated or closed, that the pressure on both sides of the piston will become equalized by reason of the 30 water passing through the by-passes 37 and 38. When the piston is thus equalized the valve 17 acts as a check valve and closes by reason of the difference in pressure between the inlet side 10 and the outlet side 11. It 35 will also be further noted that the weight of the piston together with the valve 17 assists in seating the valve 17 on the seat 16^a when the pressure is equalized on both sides of the piston.

40 What I claim is:

1. In a valve of the class described, in combination, a casing divided into two chambers by a partition arranged transversely thereof, said partition having a centrally disposed opening therethrough, said lower chamber having inlet and outlet openings therein, and a valve seat, a valve co-operat-

ing with said seat and removably connected to a stem, a piston in said upper chamber having a projection passing through said partition and removably connected to said valve stem, a relief device above said piston comprising a balanced valve having two valve members connected together, valve seats therefor, said seats being apertured and communicating with a passageway to the boiler, and means responsive to the height of water in the boiler for actuating said relief device to control the operation of said main valve. 60

2. A feed water regulator including a chambered casing, a vertically movable valve and valve stem therein, an apertured partition across said chamber through which said stem passes, a piston on said stem above said partition, said stem and piston being provided with an opening forming a by-pass, a relief valve operatively arranged in the upper part of the casing for vertical movement therein, means for moving said relief valve including a horizontally disposed arm pivotally mounted on said casing and operatively associated with the stem of said valve, a hollow member at one end of said arm, and a counter-weight near the other end thereof, 75 and communicating means between said hollow member and the boiler whereby a liquid or a vapor may be delivered to the former as conditions in the latter change.

3. In a device of the class described, a 80 valve casing, a valve seat therein, a valve for said seat removably carried by a stem, a piston at the other end of the stem removably associated therewith, a key passing through said stem for securing said piston thereto, 85 an apertured partition in said casing disposed between the piston and the key, and a relief device above said piston including a balanced valve operative by the height of the water in the boiler. 90

In testimony whereof I have signed my name to this specification on this 6th day of March A. D. 1923.

HEINRICH A. W. PETERSEN.
